AIR CONDITIONER

Willis Bonner, Duncan, Okla.

Application February 8, 1936, Serial No. 62,999

6 Claims. (Cl. 261—92)

This invention relates to air conditioners or moisteners whereby fresh moist air may be discharged into a room.

The general object of the invention is to provide an air conditioner of this type in which a fan is used for the purpose of spraying the water into the air, and another fan used for discharging the air into the room, the first one of these fans being operated by the normal passage of air from the exterior of the room into the interior of the room.

Another object is to provide a structure of this character in the form of a box or casing of any suitable character having an inlet opening at one end and an outlet opening at the other, and provided with a water receptacle in its bottom, and the provision of a fan adjacent the air inlet opening and operated by the air passing through this opening, which fan dips into the water, and as it rotates, discharges a spray into the air of the casing, and the provision of a second fan at the outlet opening of the character also operated by the normal current of air and which acts to propel the air into the room.

Other objects will appear in the course of the following description.

My invention is illustrated in the accompanying drawing wherein:—

Figure 1 is a longitudinal section through a conditioner constructed according to my invention;

Figure 2 is a section on the line 2—2 of Figure 1;

Figure 3 is a face view of the woven or water absorbent baffle.

Referring to this drawing, 10 designates a casing which may have any suitable length, height or width, and which is provided with an inlet opening 11 at its rear end, an outlet opening 12 at its forward end, and a pipe 13 of any desired length leading from this outlet opening. The lower portion of the casing is formed to provide a water tank or receptacle 14. Supported in suitable bearing brackets 15 is an air propelled fan 16, the blades of which dip into the water. This fan is rotated by the natural flow of air through the opening 11 to the opening 12. Between the opening 12 and the fan are disposed one or more baffles mounted upon screen frames 17 and 18; preferably these baffles include a sheet of fine wire netting and a sheet of woven material having large interspaces between the threads, as shown in Figure 3. Disposed forward of the opening 12 within the pipe or outlet 13 is a second fan 18 which is motor driven. This fan is mounted

upon a transversely extending support 19 which may support the motor 20.

The inlet opening of the casing is preferably screened by relatively coarse wire netting having a $\frac{1}{4}$ " mesh or a $\frac{1}{2}$ " mesh or even greater mesh. The wire cloth or netting on the screen 17 is designated 21, while the relatively coarsely woven fabric is designated 22. This, as shown in Figure 3, is formed of yarn, thread or the like, woven so coarsely as to leave ample space between the threads for the circulation of air. This fabric 22 absorbs moisture and carries it up by capillary attraction into the path of the air stream. Preferably a coarse wire netting designated 23 extends across the opening 12. The screen wire 22 is used for preventing the water from misting into the room. The number of baffles 17 and the placing of these baffles depends on the power of the motor and general conditions of the room where the air conditioner is located. Thus if the air conditioner is placed in a store where space is small and damage would be caused by moisture, it would be necessary to hold all the water in check from passing into the room though the woven baffles 22 would moisten the air. If there were plenty of room, fewer baffles would be used.

The casing may be of any desired length, as before stated, and may be made small enough to be disposed within a window opening or large enough to be used for air conditioning a relatively large area. Where the natural flow of air is strong, the fan 18 may be omitted as this natural flow of air, under these circumstances, will cause the rotation of the fan 16, which will cause a spray of water into the air and the moistening of the air even if very few or no baffles are used. On the other hand, if the natural flow of air is not strong enough, it is necessary to provide the fan 18 which will positively draw the air through the casing 10 and eject it into the room.

I do not wish to be limited to the exact form of the casing nor the proportions illustrated as obviously these might be varied in many ways without departing from the spirit of the invention as defined in the claims.

What is claimed is:—

1. An air conditioner of the character described, comprising a casing, means for retaining water in the lower portion of the casing, the casing having an inlet opening at one end and a discharge opening at the other, a fan the blades of which dip into the water of the casing, the fan acting to throw water from the blade tips into

the upper portion of the casing, a power operated fan located at the discharge opening of the casing, and a baffle of permeable material interposed between the fans and partitioning the casing from and above the surface of the water therein.

2. An air conditioner of the character described, comprising a casing, means for retaining water in the lower portion of the casing, the casing having an inlet opening at one end and a discharge opening at the other, a fan the blades of which dip at their tips only into the water of the casing, the fan when rotated acting to throw water into the upper portion of the casing, a power operated fan located at the discharge opening of the casing, and a woven material baffle located between the first fan and the discharge opening and in such proximity to the first fan as to have the water drawn against the 20 baffle as it is thrown from the blades.

3. An air conditioner of the character described, comprising a casing, the lower portion of which is formed to hold water, the casing having an inlet opening at one end and a discharge opening at the other, a fan disposed adjacent the inlet opening, the blades of which dip into the water of the casing, a power operated fan located at the discharge opening of the casing and baffles depending from the top of the casing and 30 extending into the water, each of said baffles comprising a sheet of fine wire netting, and a spaced sheet of coarsely woven textile fabric, the fabric having relatively large interspaces between the threads through which air may readily 35 pass.

4. An air conditioner of the character described comprising a casing, means for retaining water in the lower portion of the casing, the casing having an inlet opening at one end and a 40 discharge opening at the other end, a fan the blades of which dip at their tips only into the

water in the lower portion of the casing, the fan when rotated acting to throw water into the upper portion of the casing, a power operated fan located at the discharge opening of the casing, and a baffle forming a partition in the casing and disposed between the fans and in relatively close proximity to the first mentioned fan and comprising two spaced parallel fabricated sheets, one of said sheets being in the nature of relatively closely woven wire and the other of 10 the sheets being in the nature of a woven textile material of absorbent character and having its lower edge immersed in the water.

5. An air conditioner of the character described, comprising a casing, means for retaining water in the lower portion of the casing, the casing having an inlet opening at one end and a discharge opening at the other, a fan, the blades of which dip into the water of the casing, the fan acting to throw water from the blade tips 20 into the upper portion of the casing, a power operated fan located at the discharge opening of the casing, and a baffle wall of woven permeable material between the fans and completely partitioning the casing from the top of and above 25 the water therein.

6. An air conditioner of the character described, comprising a casing, means for retaining water in the lower portion of the casing, the casing having an inlet opening at one end and a 30 discharge opening at the other, a fan, the blades of which dip into the water of the casing, the fan acting to throw water from the blade tips into the upper portion of the casing, a power operated fan located at the discharge opening of the cas- 35 ing, and a baffle wall between the fans and comprising a woven permeable body and a body of fibrous material overlying a side of the first body.
